(57) **CLAIM**

The ornamental design for a display screen or portion thereof with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with animated graphical user interface showing a first image of my new design;

FIG. 2 is a second image thereof;

FIG. 3 is a third image thereof;

FIG. 4 is a fourth image thereof;

FIG. 5 is a front view of a display screen or portion thereof with animated graphical user interface showing a first image of my new design;

FIG. 6 is a second image thereof;

FIG. 7 is a third image thereof;

FIG. 8 is a fourth image thereof;

FIG. 9 is a front view of a display screen or portion thereof with animated graphical user interface showing a first image of my new design;

FIG. 10 is a second image thereof;

FIG. 11 is a third image thereof; and,

FIG. 12 is a fourth image thereof.

The outermost broken lines in FIGS. 1-12 show a display screen or portion thereof, and form no part of the claimed design. The other broken lines in the figures show portions of the animated graphical user interface that form no part of the claimed design.

The subject matter in this patent includes a process or period in which an image changes into another image. This process or period forms no part of the claimed design.
